HIS ATTORNEYS

1 This application relates to a printing stamp, and more particularly pertains to a hand stamp with a resilient type member which may be selectively deformed, by adjustment of a cooperating element, so the deformed print made by the type member represents predetermined data such as time, quantity, group number, order and the like.

2 The device is particularly adapted for use with porous resilient type members impregnated with ink used for price marking of goods in self-serve stores. In addition to the price, which may be expressed in ordinary decimal numerical notation in raised type, there is provided a design, such as a ring, which may be deformed by forcing it in or out at the desired location.

3 In general, the preferred embodiment of the invention includes a shaft-like handle with an ink-impregnated porous printing member made of resilient rubbery material and a thimble-like cap mounted on the handle with the type member projecting outwardly through a deformed hole in the cap. The hole in the cap is of such size that the peripheral portion of the printing member is forced to fit the deformities of the hole.

4 Therefore, it is an object of this invention to provide a printing stamp, having a resilient type member, with means to selectively deform the normal contour of the type member.

5 It is a further object of the invention to provide such a stamp in which the deforming means is so mounted on the stamp that it may be adjusted, while still on the stamp, to any selected one of a number of positions each giving a characteristic deformity at a different location on the type member.

6 With these and incidental objects in view, the invention includes certain novel features of construction and combinations of parts, a preferred form or embodiment of which is hereinafter described with reference to the drawing which accompanies and forms a part of this specification.

7 Of the drawing:

8 Fig. 1 is an elevation of the stamp without the deforming device attached and with the printing end thereof partly in section;

9 Fig. 2 is an end view of a thimble-like deforming device shaped to fit over like a cap and indent the ring of a resilient type member such as shown in Fig. 4;

10 Fig. 3 is an end view of a thimble-like deforming device shaped to fit over and cause a protuberance in the ring of a type member like that of Fig. 4;

11 Fig. 4 shows the printing surface of a resilient

12 type member bearing a relief numeral character surrounded by a relief ring design;

13 Fig. 5 shows the printing end of a stamp like that of Fig. 1 with a deforming device like that of Fig. 2 attached;

14 Fig. 6 shows the printing end of a stamp like that of Fig. 1 with a deforming device like that of Fig. 3 attached;

15 Fig. 7 is a section of the printing end of the stamp of Fig. 5 on the line 7-7 thereof;

16 Fig. 8 is a section of the printing end of the stamp of Fig. 6 on the line 8-8 thereof;

17 Fig. 9 is an elevation of the stamp of Fig. 1 with the deforming device of Fig. 2 mounted thereon;

18 Fig. 10 is a top plan view of the substance of Fig. 9;

19 Fig. 11 shows the print made by the stamp of Fig. 9 with a diagrammatic showing of various other positions in which the deformation may be selectively made to represent hours or months;

20 Fig. 12 is a perspective view of the deforming device of Figs. 2, 5, 7 and 9.

21 The preferred embodiment of the invention consists of a wooden handle having a shaft portion 20 (Fig. 1) of cylindrical shape except for the printing end 21 which is a truncated cone with the truncated end bored to receive a porous rubber type member 22.

22 A typical type member (Fig. 4), looked at from the printing surface, has a numeral design 23, in relief, surrounded by a ring design 24, in relief.

23 Referring to Figs. 2, 5, 7, 9, 10 and 12, a thimble-like shaped member having a conical skirt portion 25, with a beading 26 around the larger end, has the smaller end closed except for a flanged opening 27. The thimble is of such dimensions as to fit over the conical end 21 of the handle, the opening 27 permitting passage therethrough of type member 22 with a squeeze fit. Flange 27 has an inwardly projecting formation 28 which makes a deformation 29 (Fig. 5) in the ring 24 of the resilient type member which will make a print 30 (Fig. 11) with a deformed circle 31, the deformation appearing at the "9" position considering the ring divided into positions according to the position of the hour characters on a clock face.

24 The beading 26 (Fig. 9) has a locating mark 32 corresponding to the position of formation 28 which may be used in conjunction with position marks 33 on the conical end of the handle, with which the type member is properly oriented, to select the place of deformation.

The top 34 (Fig. 10) of the handle may have the numerical data 35 printed thereon to correspond with that in the type member associated therewith and oriented so as to aid the user in using the stamp so the print will be right side up.

In the modified form of the invention the thimble-like member is formed as in Fig. 3, with the deforming contour 36 projecting outwardly to give the ring of the type 22 (Fig. 6) an outward bulge.

The thimble-like member is rotated so the mark 32 is lined up with the desired position mark 33 and, as so adjusted, the device is used as a hand stamp. When it is desired that the deformation appear at another place, the thimble-like member is rotated to the new position without removing it from the handle.

It will be evident that more than one deformation may be made in the flange of the thimble-like member, if desired.

Although the preferred embodiment shows the invention as incorporated in or comprising a hand stamp, it is evident that the principle is not confined to hand operation, the type member and deformor, obviously, being subject to operation by machine, as well. Moreover, the circular design of the deformable portion of the type member is not to be deemed as a limiting factor as, for instance, a polygonal design may do as well.

While the form of the device herein shown and described is admirably adapted to fulfill the objects primarily stated, it is to be understood that it is not intended to confine the invention to the one form or embodiment herein disclosed, for it is susceptible of embodiment in various other forms.

What is claimed is:

1. In a hand stamp, in combination, a handle; a resilient type member mounted on the handle;

and a thimble-like member mounted on the handle over the type member, said thimble-like member having a hole through which the type member projects, and said thimble-like member having a formation which deforms the type member.

5 2. The device of claim 1 in which the type member has a circular type design in contact with the edge of the hole in the thimble-like member and in which the hole in the thimble-like member is circular except at one point where a deformation deforms the ring design at a corresponding point.

10 3. The device of claim 2 in which the thimble-like member is rotatable on the handle to permit the deformation of the circular type design to be made at a selected point on the circle.

15 4. In a hand stamp, in combination, a resilient type member having on the printing surface thereof a raised numeral design surrounded by a raised circular design; and a deforming member having a deformed circular hole through which the type member projects, the edge of said hole being in squeeze contact with the outer surface of the circular design so the circular design will 20 be deformed to correspond to the deformation of the hole.
